3 Claims. (Cl. 48—177)

1

This invention relates to gas holders of the lift-type and particularly an improved gas holder incorporating adjustable guide roller units secured on the various sections of a holder and carrying rollers which are adapted to roll on surfaces on vertical guide members to guide the sections of the holder during their movement between their expanded and their collapsed positions.

This application is a division of my application Ser. No. 615,337, filed Sept. 10, 1945, now Patent No. 2,551,873, issued June 20, 1950.

Telescoping lift-type gas holders usually have cylindrical sections which slide vertically within each other, while these sections are surrounded by a guide frame structure which includes vertical guide members located at spaced points about the holder. The movable sections of a holder are provided with rollers which are adapted to roll on surfaces on the vertical guide members to guide the holder sections during their movement between their expanded positions and their collapsed positions.

Gas holders usually are relatively large structures and have considerable surface area with the result that relatively large forces are exerted on the gas holder sections at times, as for example during high winds. The guide rollers must guide the holder sections and permit them to move freely at all times. Hence, the guide rollers and supporting means therefore must be rugged enough to withstand relatively great forces.

Although gas holder sections and the associated guide frame structure are fabricated and erected with a high degree of skill, it is practically impossible to initially position the rollers so that they will accurately guide the gas holder sections without binding on the guide members and interfering with free movement of the holder sections. It is usually necessary after erection of a holder and the associated guide frame structure to adjust the guide rollers during initial movement of the holder sections between their collapsed and expanded positions to insure that each section is free to move in all portions of its range of movement and to also insure that each section is accurately guided in all portions of its range of movement.

An object of this invention is to provide an improved gas holder in which the movable sections are provided with mounting surfaces adjacent the vertical guide members of the guide frame structure and have adjustably secured against these mounting surfaces guide roller units which carry rollers adapted to roll on surfaces on the guide members.

2

A further object of the invention is to provide an improved gas holder of the type described and in which the mounting surfaces and guide roller units are arranged to permit the guide roller units to be adjusted radially and laterally of the holder sections.

Another object of the invention is to provide an improved guide roller unit which is adapted to be incorporated in a gas holder of the type described.

A further object of the present invention is to provide an improved guide roller unit of the type described which is extremely rugged and is capable of withstanding substantial force.

15 Another object of the invention is to provide a guide roller unit of the type described which can be readily and economically constructed from standard structural members.

Another object of the invention is to provide an improved guide roller unit of the type described which can be fabricated as a complete unit and shipped to the point of installation.

20 Another object of the invention is to provide an improved guide roller unit of the type described which can be readily installed and which incorporates means to readily permit the adjustments which are required to insure proper operation of the roller units and of the holder sections.

25 Another object of the invention is to provide an improved guide roller unit of the type described in which the rollers are supported on a structure fabricated from a plurality of elements which are arranged so that the various elements reinforce and strengthen each other so that the rollers are rigidly supported and will be maintained in accurate alignment when subjected to forces of great magnitude.

Other objects of the invention and features of 30 novelty will be apparent from the following description taken in connection with the accompanying drawings in which

Figure 1 is a fragmentary sectional view of an 35 expanded multiple lift gas holder provided by this invention;

Figure 2 is a fragmentary sectional view of the gas holder shown in Figure 1 with the sections of the holder shown in their collapsed positions;

50 Figure 3 is a plan view of one of the guide roller units employed in the gas holder shown in Figures 1 and 2 and

Figure 4 is a side elevation of the guide roller unit shown in Figure 3.

55 Lift-type gas holders are commonly used for

the storage of gas in quantities in the order of from 50,000 to 15,000,000 cubic feet. Such gas holders are constructed with one or more lifts whereby the volume of the gas holder may be increased or decreased as required to accommodate the supply of gas on hand. Such lift-type gas holders, as are more particularly illustrated in Figures 1 and 2, are constructed with a circular tank 10 adapted to hold water at least in the portion adjacent the periphery, a guide-frame structure indicated generally by the reference numeral 12, and a gas-tight bell indicated generally by the reference numeral 14 mounted for vertical movement and guided by means including rollers 18 and 20 adapted to roll on vertical guides 13 forming part of the guide-frame structure 12. A skirt 20 of the bell 14, which, if desired, may be made extensible by means of one or more telescoping extensions 22 and 24, is immersed in the water in tank 10, thereby forming a gas-tight enclosure. There is thus provided a gas holder, the capacity of which may be increased or decreased as required to accommodate the quantities of gas on hand.

Although only one vertical guide member 13 is illustrated in the drawings, it is to be understood that the guide frame structure 12 includes a plurality of such guide members and that they are located at uniform intervals about the circumference of the gas holder, as is customary in gas holders of this type. Likewise, it is contemplated that adjacent vertical guide members 13 may be connected together with braces and tie rods, not shown, to maintain them in their vertical positions, and to assist them in withstanding the forces to which they are subjected.

The present invention relates particularly to gas holders of the general character described above and incorporates in such a structure certain features of novelty as will be pointed out which provide a stronger structure which may be assembled in less time and/or with less labor than structures heretofore available in the prior art.

In a multiple-lift gas holder the skirt and skirt extensions are severally known as lifts. The skirt 20 and extensions 22 and 24 consequently may be referred to herein sometimes as lifts 20, 22 and 24, respectively.

Each pair of adjacent lifts is provided with complementary gripping and sealing means as best shown in Figure 2, whereby the inner lift of the pair, as it is raised, engages and lifts the outer one of the pair with a gas-tight engagement. Suitable gripping and sealing means as illustrated comprise hydraulic cups 40 and grips 42 formed in the shape of an upwardly opening annular channel, and a downwardly opening annular channel, respectively, of such dimensions that the inner radius of the grip is intermediate the outer and inner radii of the cup. Hence, in the expanded position, the outer side 44 of cup 40 lies inside the grip 42 and the inside wall 46 of the grip 42 lies inside the cup 40. The wall 46 of the grip 42 is thus immersed in the water retained in the cup 40 and forms a gas-tight wall in the expanded position. The depth of the cup 40 is desirably equal to the depth of the grip 42 so that the top edge of wall 44 of the cup 40 will engage the top 48 of the grip 42 at the same time that the bottom edge of the wall 46 of the grip 42 engages the bottom 50 of the cup 40. Inner wall 52 of cup 40 also forms part of the lift. Desirably, though not necessarily, the wall 52 is made of separate sheets welded to the remainder of the lift. The outer wall 54 of the grip 42 is similarly

constructed. The sheets forming the walls 44, 46, 48, 50, 52 and 54 desirably are made of heavier stock than the other portion of each lift in order to give added strength to the lift structure. At the bottom of the outermost lift 24 there is provided an out-turned annular flange 56 in place of a cup. It is constructed as the cup 40 except the outside wall 44 is omitted. Similarly no grip is provided at the top of the innermost lift 20. There is provided instead a circular convex dome or roof 58 welded at its periphery to the top of the lift, thereby forming with the lifts 20, 22 and 24 the gas-tight bell 14. If desired, the height of the lift 20 may be extended by means of plates 60 welded to the top of the skirt and in turn to the periphery of the dome. The height of the inner lift 20 is thus made equal to that of the other lifts.

In the landed or collapsed position the dome, as shown in Figure 2, is supported against collapse by a supporting structure 61 of any suitable design. Inasmuch as such structures are common in the art, it will not be necessary to describe them in detail.

As explained in my application identified above, the lifts are provided with vertical strengthening guide rails which extend along the inside of the lifts over the entire height of the lifts. The guide rails are attached at intervals around the entire periphery of the inside of each lift. Rollers are secured to the bottoms of the rails which have a mounting to place the rollers on the outside of the lifts in position to engage the rails secured to the next lift outside of the lift on which the rollers are mounted. These guide rails and rollers keep the lifts in proper spaced relation to the tank and the next adjacent lift as the lifts are raised and lowered to provide for changes in volume of gas in the holder. Reference is made to application, Ser. No. 615,337 for the details of construction of the guide rails and rollers since these details of construction are not essential to an understanding of the particular invention described and claimed herein.

The present invention relates particularly to the roller guide units which are mounted around the outside periphery at the tops of each of the lifts. These roller guide units cooperate with rail guides 16 mounted in and forming a part of the guide frame structure 12 which surrounds the holder. To position the guide units on the lifts an angle is provided at the top of the outside of the lifts 22 and 24 at the intersection of the top 48 and inner side 46 of the grips 42. The side 46 is projected a suitable distance above the top plate 48 for this purpose. Supporting structures 107 and 108 for the outside rollers 112 and 113 are suitably fastened in these angles as more clearly shown in Figure 2. A supporting structure 110 is mounted on the dome 58. The outermost plates 112 of the dome desirably are made of heavy stock and are reinforced by brackets 114 to provide an adequately strong base for support 110.

It is to be understood that a plurality of supporting structures 107, 108 and 110 are provided, there being one of each of these supporting structures radially inwardly of each of the vertical guide members 13. As is best shown in Fig. 2 of the drawings, the supporting structures extend radially outwardly so that each terminates adjacent the inner face of one of the guide members 13. In addition, as is clearly shown in Fig. 2 of the drawings, the supporting structures 107, 108 and 110 are proportioned so that when the 75 lifts of the holder are in their collapsed position

the supporting structure 108 projects over the supporting structure 107, while the supporting structure 110 projects over the supporting structure 108.

Each of the supporting structures has adjacent its radially outer end a substantially horizontal mounting surface which is adapted to have detachably secured thereon a guide roller unit indicated generally by the reference numeral 116 and carrying rollers 118 and 120 which are adapted to roll on guide surfaces on a vertical guide member 18. One of the supporting structures 107 is illustrated in Figs. 3 and 4 of the drawings and as therein shown the mounting surface is formed by a flat plate 150. It is to be understood that each of the supporting structures 108 and 110 is provided with a similar substantially horizontal mounting surface adjacent its outer end and on which is secured a guide roller unit 116 of the type shown in Figs. 3 and 4.

Mounted on the mounting surface of each of the supporting structures 107, 108, and 110, is a guide roller unit 116. Each of these guide roller units has three rollers, designated 118 and 120, journaled in suitable supports. Rollers 118 are mounted on parallel axes and are positioned to roll upon the flanges 122 of I-shaped vertical guide member 18 mounted in a vertical position on the guide-frame structure 12, whereas the roller 120 is mounted with its axis normal to the axes of the rollers 118 and is positioned to roll upon the web 126 of guide member 18. The guide members 18 are suitably supported on the guide-frame structure 12 by a suitable supporting means 128 in positions which preferably are radially outwardly of the guide surfaces on the interior of the lifts 24 and 22 so that the outside rollers 120 are radially in alignment with at least some of the inside rollers. The supporting structure 128 suitably is a T, the cross-head of which is suitably fastened to the framework structure, as by welding, with its leg 130 in a vertical position and projecting radially toward the center of the structure. The web 126 of the guide member 18 is suitably fastened to the leg 130 of the support 128, as by welding. The supporting means 128 on which the vertical guide members 18 are secured may be vertical extensions of the members 164 which are secured to the exterior face of the plates forming the wall of the tank 10, as is clearly illustrated in Fig. 2.

Each of the guide roller units 116 comprises a channel-shaped bracket 132 having a web 134 and side flanges 136. The rollers 118 are mounted on the channel 132 by the shafts or trunnions 138 which are provided with retaining heads 140 and project through aligned holes in the side flanges 136. Suitable washers 142 and pins 144 complete the mounting of rollers 118. As already pointed out, the axes of the rollers 118 and the axes of the shafts or trunnions 138 are parallel. They are also normal to the side flanges 136 of the channel 132. The center roller 120 is mounted between two parallel plates 146 which are welded, or otherwise fastened, to the web 134 and side flanges 136 of the channel 132. The plates 146 are parallel one to another and normal to the side flanges 136 and the web 134. The plates 146 project slightly beyond the front flange 136 of the channel 132 as required properly to position the roller 120. The front flange 136 of the channel 132 is cut away as required to permit plates 146 so to project and to permit free rotation of the roller 120. The roller 120 revolves on a shaft 148 which is normal to the shafts 138 and extends through

aligned holes in the plates 146. The web 134 of channel 132 is adjustably mounted on the mounting surface formed by a plate 150 which is secured in a horizontal position on top of each of the supports 107, 108, and 110. The web 134 is perforated with longitudinally elongated slots 152, whereas the plate 150 is provided with correspondingly positioned transversely elongated slots 154, as is best shown in Fig. 3 of the drawings.

The slots 152 in the web 134 of the channel 132 and the slots 154 in the plate 150 are located in such manner that when the channel 132 is placed on the plate 150 the centers of the slots in the channel substantially coincide with the centers of the slots in the plate. The channel 132 is fastened to the plate 150 by suitable fastening means, such as the bolts 156. By loosening the bolts 156, the channel 132 may be shifted transversely throughout the length of slots 154 and longitudinally throughout the length of slots 152. Within limits, therefore, the position of the guide roller units is easily adjustable both radially and laterally of the mounting surface.

The construction just described provides a guide roller unit 116 which can be constructed economically and is very satisfactory. The channel 132, which is one of the principal parts of the guide roller unit, is a standard structural steel shape. This channel has great strength to resist forces in the plane of the web 134 or of the flanges 136, but has little strength to resist twisting forces. However, the channel is reinforced and strengthened by the plates 146 which extend transversely of the channel 132 and are secured to the web and flanges of the channel. The plates 146 stiffen the channel and prevent twisting of the channel with the result that the channel 132 provides a rigid support for the rollers 118. Similarly, the plates 146 are reinforced and stiffened by the channel 132, particularly by the flanges 136 which are secured to the plates 146. Hence, the plates 146 provide a rigid support for the roller 120.

The shafts 138, on which the rollers 118 are mounted, extend through aligned holes in the flanges 136 on the channel 132. The flanges 136 are spaced apart a considerable distance so that the shafts 138 are rigidly held with respect to the channel 132 and the rollers 118 will not get out of alignment because of movement of the shafts 138 relative to the channel 132. As explained above, the channel 132 is reinforced and strengthened by the plates 146 so that the channel has great strength to resist twisting forces, that is, forces tending to move the shafts 138 out of alignment with each other. Furthermore, the bolts 156 which secure the channel 132 to the plate 150 are located directly beneath the shafts 138 so the plate 150 is effective to reinforce the channel and to prevent twisting of the channel which would result in misalignment of the shafts 138.

The guide roller unit 116, therefore, rigidly maintains the rollers 118 and 120 in alignment even under conditions in which substantial forces are exerted on the rollers, as for example during a high wind storm. As the rollers 118 and 120 are maintained in alignment at all times, the rollers roll freely on the guide members 18 and do not interfere with movement of the lifts of the holder.

The invention may be more fully understood by referring generally to the method of construction. The first thing to be constructed is the tank 10. A suitable bottom 158 is formed by

welding together sheets upon a suitable foundation. The bottom is circular, while I-beams 168 may be welded along radii at intervals along the bottom 158 to hold the lifts 20, 22, and 24 off the bottom. About the circumference of this bottom is then erected the wall of the tank. The wall of the tank is suitably formed by welding together steel plates. As more clearly shown in Figure 2, these plates may be proportioned in weight according to the pressure of water that they are required to support. Thus the bottom plate 160 may be substantially thicker than the top plate 162.

The guide-frame structure 12 is built up from the top of the tank 10 in the customary manner. Suitable reinforcing beams 164 project downwardly from this guide-frame structure and are welded to the exterior wall of the tank 10.

Either before or after or simultaneously with the building up of the tank and the guide-frame structure 12, the lifts are fabricated in the position shown in Figure 2, and prior to this, or afterward, or simultaneously therewith, the supporting structure 61 is erected in accordance with the usual practice in the art.

The outside roller supports 107, 108, and 110 are welded in place either after or during construction of the lifts. The guide roller units 116 are then mounted and are initially adjusted.

The tank 10 is now filled with water and air is pumped into the tank as required to raise the bell 14. As the bell 14 is being raised, the guide roller units 116 are adjusted as required to permit unrestrained movement of the lifts of the holder and at the same time insure that the lifts will be accurately guided by the guide rollers.

In addition during this initial raising of the lifts of the holder, work may be performed on them, as for example completion of the welding of the seams in these sections.

The adjustable guide roller units provided by this invention make it possible effectively and economically to effect the above-described operations of adjusting the guide roller units and of welding the seams in the lifts. By the simple expediency of loosening bolts, it is possible to realign or adjust the guide roller units both radially and laterally as may be necessary to accommodate the particular requirements of the gas holder. It is not practically possible so to construct a lift-type gas holder that adjustment of the guide roller units need not be made during the initial operations. Practices heretofore available make it difficult to do this and have materially increased the cost of construction since the number of manhours lost during such adjustments has been relatively large.

From the foregoing it will be seen that I have provided an improved gas holder incorporating adjustable guide roller units. The lifts of the holder have secured thereon the supporting structures 107, 108, and 110 which have horizontal mounting surfaces adjacent the inner faces of the vertical guide members 18. These mounting surfaces are adapted to have secured thereon the guide roller units 116 which carry the rollers 118 and 120 which roll on the faces of the vertical guide members 18. As explained above, the guide roller units 116 hold the rollers 118 and 120 rigidly in alignment so that the rollers move freely on the surfaces of the vertical guide members 18 even when subjected to forces of substantial magnitude. In addition, it will be seen that the guide roller units 116 are adapted to be constructed as complete units and

shipped to the point of installation. Furthermore, these units are quickly and easily installed by placing the units on the mounting surfaces on the supporting structures 107, 108, and 110, and installing the bolts 156. After a guide roller unit has been installed it can be readily adjusted both radially and laterally of the associated mounting surface so that the rollers carried by the unit will engage the faces of the guide members 18 but will not bind on these members or press against them so much as to interfere with movement of the lifts of the holder. As the adjustment of the guide roller units can be quickly and easily accomplished, this adjustment will not delay other work which may be in progress during initial raising of the lifts of a holder.

While I have described my invention with reference to particular embodiments thereof, it will be understood that variation may be made therein without departing from the spirit and scope of the invention.

I claim:

1. In a gas holder comprising a tank, a guide-frame structure mounted thereon and a gas-tight bell adapted for vertical movement within said tank and guide-frame structure, the combination of guides mounted on the interior of said guide-frame structure, each of said guides having a plurality of vertical rolling surfaces, a plurality of roller units mounted on supporting means affixed to said bell each of said units having a plurality of rollers adapted to roll upon the rolling surfaces of said guides, each of said units comprising a channel-shaped member having a web resting on a flat supporting plate comprised in said supporting means and having flanges at each side thereof normal to the radius projecting through said guides, a pair of rollers mounted on parallel trunnions projecting through the flanges of said channel, and another roller mounted on an axle supported between and normal to said parallel trunnions in two parallel plates mounted transversely of said channel-shaped member and fastened to the flanges and web thereof.

2. In a gas holder of the type having a guide frame comprising a plurality of substantially vertical guide members arranged at spaced points about the circumference of a circle, each of said guide members having on the side thereof facing the center of said circle a tangentially disposed vertical guide surface and having a pair of radially disposed vertical guide surfaces and a gas-tight bell adapted for vertical movement within said guide frame, said bell having on its exterior face radially inwardly of each of said vertical guide members a substantially horizontal mounting surface having therein a plurality of holes all of which are elongated in the direction of the plane of one of the vertical guide surfaces on the adjacent vertical guide member, the combination with the foregoing of an improved guide roller unit, said unit comprising a channel shaped member having a web resting on said horizontal mounting surface and having flanges at each side of the web running parallel to said tangentially disposed guide surface, a pair of spaced parallel plates disposed substantially perpendicular to the face of said channel member and extending transversely of said channel member, each of said plates being secured to the web and to the flanges of said channel member and being located adjacent the midportion of said channel, an axle extending through aligned openings in said plates and hav-

ing supported thereon between said plates a tangentially disposed roller adapted to roll on the first vertical surface on one of said vertical guide members, the flanges on said channel member having aligned openings therein to one side of said plates and aligned openings to the other side of said plates, each pair of aligned openings having supported therein a trunnion extending from a side face of the channel member and having mounted thereon a roller which is adapted to roll on the radially disposed guide surface on one of said vertical guide members, the web of said channel member having therein a plurality of holes which are elongated in the direction perpendicular to that in which the holes in the supporting surface are elongated, the holes in the web of the channel being located so that when said channel member is placed against said mounting surface the centers of the holes in the channel and in the supporting surface substantially coincide, and bolts extending through the holes in the web of said channel member and in said supporting surface.

3. In an improved guide roller unit for multiple-lift-type gas holders in combination: a tank, a closed lift mounted within the tank, a guide-frame surrounding the lift and mounted on the tank, vertical guides mounted in the frame in spaced relationship around the lift, a supporting structure secured to the upper peripheral surface of a lift and having a flat supporting surface, a channel-shaped member having a web resting on said flat supporting surface and having flanges at each side of the web running normal to a radius of the lift running above the center of said web, a pair of spaced parallel plates disposed substantially perpendicular to a tangentially disposed face of said channel member and extending transversely thereof, each of said plates

being secured to the web and to the flanges of said channel member, said plates being located adjacent the mid portion of the channel member, an axle extending through aligned openings in said plates and having supported thereon between said plates a first roller adapted to roll on the guiding surface of a vertical guide, the flanges on said channel having aligned openings therein to one side of said plates and aligned openings therein to the other side of said plates, each pair of aligned openings having supported therein a trunnion extending from a side face of said channel and having mounted thereon a second roller rotatable about an axis perpendicular to the axis of said first roller, each of said second rollers being adapted to roll on radially disposed guiding surfaces of the vertical guide, the web of said channel having therein a plurality of holes which are adapted to receive bolts by means of which said assembly may be secured in adjusted guiding position on the surface of the supporting structure.
